(57) **CLAIM**

The ornamental design for a microphone including a microphone capsule and modular gooseneck section, as shown and described.

DESCRIPTION

FIG. 1 is a top perspective view of a microphone including a microphone capsule and modular gooseneck section; FIG. 2 is a bottom perspective view thereof; FIG. 3 is a front elevation view thereof; FIG. 4 is a rear elevation view thereof; FIG. 5 is a top plan view thereof; FIG. 6 is a bottom plan view thereof; FIG. 7 is a right side elevation view thereof; FIG. 8 is a left side elevation view thereof; FIG. 9 is an enlarged partial view thereof, taken from FIG. 1; FIG. 10 is another enlarged partial view thereof, taken from FIG. 1; FIG. 11 is an enlarged partial view thereof, taken from FIG. 2; FIG. 12 is another enlarged partial view thereof, taken from FIG. 2; FIG. 13 is an enlarged top plan view thereof; FIG. 14 is an enlarged bottom plan view thereof; FIG. 15 is an enlarged front elevation view of the microphone capsule portions of the microphone including a microphone capsule and modular gooseneck section; FIG. 16 is an enlarged rear elevation view thereof; FIG. 17 is an enlarged top plan view thereof; FIG. 18 is an enlarged bottom plan view thereof; FIG. 19 is an enlarged right side elevation view thereof; FIG. 20 is an enlarged left side elevation view thereof; FIG. 21 is an enlarged perspective view thereof; FIG. 22 is a front elevation view of a microphone including a microphone capsule and modular gooseneck section with the microphone capsule removed to show only the modular gooseneck portion; FIG. 23 is a rear elevation view thereof; FIG. 24 is an enlarged top plan view thereof; FIG. 25 is a bottom plan view thereof; FIG. 26 is a right side elevation view thereof; FIG. 27 is a left side elevation view thereof;

(Continued)

FIG. 28 is an enlarged partial view thereof, taken from FIG. 22;

FIG. 29 is an enlarged partial view thereof, taken from FIG. 20; and,

FIG. 30 is an enlarged partial view thereof, taken from FIG. 21.

The broken lines illustrate portions of the microphone including a microphone capsule and modular gooseneck section that form no part of the claimed design.
